UNITED STATES PATENT OFFICE

ERIK H. ALDEBORGH, OF POUGHKEEPSIE, NEW YORK, ASSIGNOR TO STANDARD GAGE COMPANY, INC., OF POUGHKEEPSIE, NEW YORK, A CORPORATION OF NEW YORK

TUBULAR GAUGE

Application filed January 30, 1929. Serial No. 336,104.

This invention relates to a tubular gauge, Figures 1 and 2, for the gauging member a single piece of commercial steel tubing 10 is provided of the required length and outside diameter, and with a heavy wall, and the ends of said member 10 are shouldered slightly as 55 at 11.

The present invention discloses a gauge 10 which is also disclosed in an application which was filed on April 4, 1928, under Serial No. 267,203.

The object of the invention is to construct a gauge of this class for use with large diameters that shall be very light in weight in proportion to its size.

Another object of the invention is to construct a gauge in which the gauging member is formed from a piece of straight commercial tubing.

A still further object is to construct a gauge from tubing, and provide means for mounting said tubing upon a handle in an interchangeable and reversible manner.

Also such a tubular gauging member may be mounted on one or both ends of any suitable handle, in such a manner that one may be designed for a Go and the other for a No Go measurement.

With these and other objects in view, my invention consists in certain combination and construction of parts as will hereinafter be fully described and claimed and fully illustrated in the accompanying drawings which 35 form a part hereof and in which like figures of reference refer to corresponding parts in all of the views, but it is understood that slight changes may be made without departing from the spirit of the invention.

In the drawings:

Figure 1, is a partial sectional view of my invention.

Figure 2, shows an end view of this form 45 of gauge.

Figure 3, shows a partial sectional view of a modified form of construction.

Figure 4, shows an end view of the same.

Referring to the drawings and particular- 50 ly to the preferred construction shown in

For mounting and supporting said gauging member, there is provided a handle 12, which is formed with external threads 13 and the internal threads 14; while mounted 60 on said handle 12 is a knurled ring 15 threaded thereon to form a shoulder for a mounting ring 16, which is provided with a bore of larger diameter than the diameter of said handle, and an outer diameter adapting it 65 to fit within the shouldered end 11 of the member 10.

Mounted in the other end of the member 10, is a bushing member 17, which is formed with a flanged head 18 adapted to engage the 70 flanged end 11 of the member 10; while the body of said member 17 is threaded to receive the threaded end of the handle, upon which it is mounted.

The external diameter of the body of said 75 member 17 being less than the internal diameter of the gauging member 10, and the length also being less than the distance between the inner faces of the ring 16 and the head 18, so that as the bushing member 17 is threaded 80 and drawn up on the threaded end of the handle 12, the gauging member 10 will be gripped therebetween and held in a rigid manner.

For preventing accidental loosening of the 85 members, the head 18 is recessed as at 19 and provided with a hole through which is passed a screw 20 which is threaded into the threaded end 14 of the handle 12.

In the modified form shown in Figures 3 90 and 4, the gauging member 10 is not shouldered, but the mounting ring 21 is formed with a shoulder 22, and a second mounting ring 23 is provided which is also shouldered as at 24, and provided with a recessed end 95 25 having a hole for a screw 26 which is threaded into the end of the handle 26; said handle being provided with the ring 15 which is threaded thereon in an adjustable manner, so that the mounting rings 21 and 23 may 100

grip the ends of the gauging member 10 and hold the same.

It will thus be seen that the gauging members are both removable and reversible with respect to the handle.

Having thus described my invention, what I claim as new and desire to secure by Letters Patent, is:

1. A gauge of the class described, comprising in combination with a handle having a threaded end, of a tubular gauging member formed with a circumferential recess in each end thereof, means for securing said gauging member to said handle in both a detachable and reversible manner comprising a bushing threaded upon said handle, a flange formed on one end of said bushing and adapted to engage the shoulder formed by the recess of the gauging member, at end of said 20 gauging member, a mounting ring mounted on said handle and adapted to engage the similar shoulder at the other end of said gauging member, a locking ring threaded on said handle in contact with said mounting 25 ring, and a locking screw threaded into the end of said handle and engaging said bushing.

2. A tubular gauge of the class described, comprising in combination with a handle 30 provided with external threads and an internal threaded bore at one end, and a straight tubular gauging member, of a pair of centering and mounting members adapted to be engaged by the ends of said tubular 35 gauging member, and means for securing the same to said handle comprising a screw engaging one of said mounting members and threaded into the internal threaded bore of said handle, and a ring forming a shoulder 40 for the other mounting member and secured upon the external threaded portion of said handle.

In testimony whereof I affix my signature.
ERIK H. ALDEBORGH.
